UNITED STATES PATENT OFFICE.

WILLIAM HENRY STAYNES, OF LEICESTER, ENGLAND.

BUFFING-ROLL.

1,029,406.

Specification of Letters Patent. Patented June 11, 1912.

Application filed October 20, 1911. Serial No. 655,752.

To all whom it may concern.

Be it known that I, WILLIAM HENRY STAYNES, a subject of the King of Great Britain, residing at Leicester, in the county 5 of Leicester, England, have invented certain new and useful Improvements in Buffing-Rolls, of which the following is a specification.

This invention relates to improvements 10 in machinery employed in the manufacture of leather.

The invention consists of a roll or cylinder provided with a series of ribs having abrasive working faces particularly adapted 15 for use in what is known as the buffing operation *i. e.* of removing by abrading the grain side of the hide or skin. Such a roll or cylinder may be made of wood with the ribs or bars cut or otherwise formed on the 20 face thereof and the face of the said ribs or bars may be covered with abrasive material such as sandpaper secured thereon by cement or other suitable adhesive, or in any other convenient manner. For the buffing 25 operation hereinbefore mentioned the ribs or bars are arranged in series converging to a point approximating a V so that as the roller revolves the apices of the bars act on the center of the hide or skin and the 30 divergence of the bars gradually buffs or abrades the skin toward the outer edges of the same.

One form of a buffing roll according to this invention is illustrated in the accompanying drawing, wherein:—

Figure 1 is an elevation of the roll. Fig. 2 is a section on the line *a—b* of Fig. 1, and Fig. 3 is an end view.

Like parts are designated by the same reference characters in all the figures.

Referring to the drawing, 1 is the roll or cylinder which may be suitably attached to a spindle 2 mounted and rotated in any convenient manner. The roll 1 may be made 45 of wood, metal or any other suitable material such for example as carborundum or solid emery, and is provided with a series of

ribs or bars 3 having abrasive or working faces 4.

As shown in Fig. 1, the ribs or bars 3 are, for the buffing operation, arranged in series converging to a point approximating a V, the apices of the said V shaped bars being located approximately in the middle of the roller so that as the latter rotates, in 50 the direction indicated by the arrow in Fig. 1, a divergence of the said ribs or bars 3 in opposite lateral directions from the center outward will take place and thus the hide or skin will have imparted thereto a 55 buffing or abrading operation which is effected in a direction from the middle toward the outer edges of the same. The ribs overlap each other at the middle of the roll and the overlapping terminals closing the 60 ends of the channels between the ribs are narrowed as shown. By this means the 65 abrading surface is rendered continuous at the middle of the roll at its middle portion, but in a zigzag direction thus making the 70 abrading operation more effective than if the overlapping were omitted, while, by reason of the terminals of the ribs being 75 diminished, the abrading action at the middle of the roll is equalized with that of other portions.

The ribs or bars 3 may be integrally formed with the roll 1 or they may be attached to the face of the roll in any suitable manner. The working faces 4 of the ribs 80 3 may be covered with abrasive material such as sandpaper secured thereon by cement or other suitable adhesive, or in any other convenient manner. If desirable however, the ribs or bars 3 may be without 85 an abrasive covering such as just described, this being especially the case when the ribs or bars are formed upon a roll or cylinder of carborundum or solid emery. Other arrangements of the ribs or bars 3 on the roll 90 1 may be employed although they may not be so suitable for the operation mentioned, but nevertheless may be convenient for other analogous operations.

What I claim then is:—

A buffing roll having projecting ribs on its surface with abrasive working faces, said ribs being arranged in series converging to a point approximately a V so that as the roll rotates in the direction of the apices of the ribs the latter, by divergence from their apices, act upon the work from the center thereof laterally outward toward the edges

of the same, the ends of said ribs overlapping each other and being diminished in width. 10

In testimony whereof I affix my signature in presence of two witnesses.

WILLIAM HENRY STAYNES
